Attorney

UNITED STATES PATENT OFFICE.

HENRY W. YOST, OF DAYTON, OHIO.

DESIGN FOR A CASING FOR A FLUID-MOTOR.

56,720.

Specification for Design.

Patented Nov. 30, 1920.

Application filed February 1, 1919. Serial No. 274,572. Term of patent 14 years.

To all whom it may concern:

Be it known that I, HENRY W. YOST, a citizen of the United States, residing at Dayton, in the county of Montgomery and State of Ohio, have invented a new, original, and ornamental Design for a Casing for a Fluid-Motor, of which the following is a specification, reference being had to the accompanying drawings, forming part hereof.

Figure 1 is a top plan view of a fluid mo-

tor showing my new design. And Fig. 2 is a front view thereof.

I claim:

The ornamental design for a casing for a fluid motor, as shown.

HENRY W. YOST.

Witnesses:

HOWARD S. SMITH,
R. M. GALLOWAY.
